UNITED STATES PATENT OFFICE.

CECIL R. JONES, OF PHOENIX, ARIZONA.

ATTACHMENT FOR INTERNAL-COMBUSTION ENGINES.

Application filed May 3, 1927. Serial No. 188,516.

This invention relates to a charge heating and mixing device for internal combustion engines and it has for its object to provide a simple and inexpensive device of this nature adapted to be located in the path of the fuel charge from the carburetor to the intake manifold, and comprising a plurality of electrically heated surfaces and means for causing the charge to travel in a tortuous path and to be successively brought into contact with a plurality of such heated surfaces, so that the charge will be thoroughly mixed, broken up and heated, before entering the combustion chambers of the engine.

15 Further objects and advantages of the invention will be set forth in the detailed description which follows.

In the accompanying drawings:

Fig. 1 is a side elevation of a heater constructed in accordance with the invention.

Fig. 2 is a vertical sectional view therethrough.

Fig. 3 is a plan view thereof with the top of the heater and mixer removed.

25 Fig. 4 is a view looking at the under face of the head of the mixer and heater and showing the upper heater.

Fig. 5 is a side elevation of the structure of Fig. 4.

30 Fig. 6 is a plan view of the upper face of the bottom of the heater.

Fig. 7 is a side view of the structure of Fig. 6.

Fig. 8 is a plan view of the heater with the top removed.

Fig. 9 is a sectional view of the central section of the heater, showing the lower heater in elevation.

Fig. 10 is a sectional view of the lower heater, and Fig. 11 is a plan view of said lower heater.

Like numerals designate corresponding parts in all of the figures of the drawing.

The device of the present invention comprises a cylindrical body 4, the upper end of which is closed by a head 2 and the lower end of which is closed by a bottom 7. In applying the device to an engine, the intake manifold is interrupted and the head 2 is connected to a pipe 1 constituting an upper part of the manifold and the bottom 7 is connected to a pipe 8, which, in turn, leads to the carburetor (not shown).

An upper unit consisting of a suitable electrically heated coil 10 has a seating in an insulating ring 9 of porcelain or other suitable

material, and is supplied with current through wire 3. The compartment within which the heating coil 10 is located is closed by a web or plate 13 of any suitable material which is bound in place between metallic rings or washers 11 and 12, in such manner as to form a fluid tight joint therearound, so that the explosive charge can never, by any means, find its way into direct contact with coil 10. The plate 13 is also bound into fluid tight contact with the lower end of a neck extension 2^a of the head 2 by means of a washer 14.

A lower heating unit comprises a cylindrical band 22 in which a ring 17 is located. Upper and lower closure plates 16 are bound against the ring 17 by means of washers 15 and form a closed chamber within which a heating coil 20 is located, said coil being supported by an insulating member of porcelain or other suitable material 21. The upper edge of the band 22 projects above the lower end of the extension formed by the neck extension 2^a and the washer 14, while the lower edge of the band 22 projects below the upper end of a neck extension 7^a of the bottom or base 7. The lower heater is held in place by screws 5 and 6 which pass through the outer casing 4 and take into the ring 17. The screw 5 has an opening formed therethrough for the passage of a feed wire 18 by means of which current is supplied to the lower heater 20. Spacing washers 19 surround the screws 5 and 6 and suitably space the lower heater within the ring or casing 4.

The direction of travel of the charge is indicated by the arrows, from which it will be seen that the incoming charge passing through the neck extension 7^a, first impinges upon the lower heated plate 16, is then caused to travel outwardly and downwardly around the lower edge of the ring 22, then upwardly outside of said ring between said ring and the casing 4, until it impinges upon the upper heated element 13 where its direction of flow is reversed and it travels downwardly over the upper edge of the ring 22 and again impinges upon a heated surface constituted by the upper plate 16, and passes finally out of the neck extension 2^a, into the pipe 1, from whence it finds its way into the combustion chambers of the engine.

From the foregoing description it will be seen that a highly efficient device for the purposes set forth is here presented. How-

ever, it is to be understood that the invention is not limited to the precise construction set forth but that it includes within its purview whatever changes fairly come within either the terms or the spirit of the appended claims.

Having described my invention what I claim is:

1. A device of the character described comprising an electric heating unit, a chamber in which said unit is located, said chamber comprising closure plates, one upon each side of said heating unit, an entrance conduit terminating adjacent one of said plates, a discharge conduit having its point of beginning adjacent the other of said plates, and means adjacent the mouth of the discharge conduit for deflecting and reversing the flow of the charge, the incoming charge impinging first upon one of said plates, then traveling around the heating unit and by such deflection being caused to impinge upon the other of said plates and then passing out of the discharge conduit.
2. A device of the character described comprising a main casing, a heater located therein comprising a heating unit, a closure plate upon each side of said heating unit, an enclosing ring extending outwardly upon each side of said closure plates, a discharge conduit for incoming fuel charge terminating adjacent one of said plates and within the confines of said ring and a conduit for conducting the charge away from the heater having its point of beginning adjacent the other of said plates and within the confines of said ring, the incoming charge impinging first upon one of said plates, then traveling around the adjacent edge of said ring, thence between the ring and the main cas-

ing, thence about the other edge of said ring and impinging upon the other of said plates and finally passing out of the second named conduit.

3. A structure as recited in claim 2 in combination with a second heater and a plate closing the same, said plate being positioned to be impinged by the charge before it passes over the last named edge of said ring.

4. A device of the character described comprising a ringlike body, a top adapted to be connected to an intake manifold, a bottom adapted to be connected to a carburetor, inwardly extending neck extensions carried by both the top and bottom, an upper heating element carried by the top, a plate enclosing the same and a lower heating element comprising a ring the upper edge of which extends above the neck extension of the top and the lower edge of which extends below the neck extension of the bottom, a heating element located within said ring, plates enclosing said heating element, one upon each side thereof, and means for supplying electric current to both of said heaters, the incoming charge passing through the neck extension of the bottom and impinging upon the lowermost plate of the lower heater, thence passing around the lower edge of the ring of the lower heater, thence passing upwardly between the ring and the main casing, thence passing over the upper edge of said ring of the lower heater after impinging upon the plate of the upper heater and thence passing out of the neck extension of the top.

In testimony whereof he affixes his signature.

CECIL R. JONES.
